Vanderminden, design U.S. Appl. No. 29/456,722, entitled Seat, filed Jun. 3, 2013, 7-pages.

(Continued)

Primary Examiner — Mimosa De(74) *Attorney, Agent, or Firm* — Heslin Rothenberg Farley & Mesiti P.C.(57) **CLAIM**

The ornamental design for a seat, as shown and described.

DESCRIPTION

FIG. 1 is a perspective view of a seat in accordance with the new design;

FIG. 2 is a front elevational view thereof;

FIG. 3 is a right side elevational view thereof;

FIG. 4 is a left side elevational view thereof;

FIG. 5 is a rear elevational view thereof; and,

FIG. 6 is a top view thereof.

The broken lines in the figures are for illustration purposes only and form no part of the claimed invention.

1 Claim, 6 Drawing Sheets(56)
